HANDLE FOR A PET GROOMING COMB

Robert W. Sleith, Wilbraham, Mass., assignor to Suburban Plastics, Inc., Three Rivers, Mass.

Filed Sept. 20, 1971, Ser. No. 182,295

Term of patent 14 years

Int. Cl. D30—99

U.S. Cl. D30—40

FIG. 1.

FIG. 2.

FIG. 3.

FIG. 5.

FIG. 4.

FIG. 1 is a side elevational view of a handle for a pet grooming comb, showing my new design, the opposite side being substantially a mirror image thereof;

FIG. 2 is a top plan view thereof;

FIG. 3 is a rear end elevational view looking from the left in FIG. 1;

FIG. 4 is a perspective view; and

FIG. 5 is a front end elevational view looking from the right in FIG. 1.

I claim:

The ornamental design for a handle for a pet grooming comb, as shown and described.
